US00D740803S

(12) **United States Design Patent**
Yamazaki et al.

(10) **Patent No.:** US D740,803 S
(45) **Date of Patent:** ** Oct. 13, 2015

(54) **PORTABLE INFORMATION TERMINAL**

- (71) Applicant: **SEMICONDUCTOR ENERGY LABORATORY CO., LTD.**, Atsugi-shi, Kanagawa-ken (JP)
- (72) Inventors: **Shunpei Yamazaki**, Tokyo (JP); **Kensuke Yoshizumi**, Kanagawa (JP)
- (73) Assignee: **Semiconductor Energy Laboratory Co., Ltd.**, Kanagawa-ken (JP)

(**) Term: **14 Years**

(21) Appl. No.: **29/448,562**

(22) Filed: **Mar. 13, 2013**

(30) **Foreign Application Priority Data**

- Sep. 21, 2012 (JP) 2012-022835
- (51) **LOC (10) Cl.** **14-02**

OTHER PUBLICATIONS

Yamazaki et al., "Portable Information Terminal", U.S. Appl. No. 29/448,562, filed Mar. 13, 2013, Specification and Drawings.

Primary Examiner — Barbara Fox

Assistant Examiner — Clesse Moore, Jr.

(74) *Attorney, Agent, or Firm* — Nixon Peabody LLP; Jeffrey L. Costellia

(57) **CLAIM**

We claim, the ornamental design for a portable information terminal, as shown and described.

DESCRIPTION

FIG. 1 is a front view of a portable information terminal showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is a top front perspective view thereof.

1 Claim, 6 Drawing Sheets
